UNITED STATES PATENT OFFICE.

GAETANO PILATI, OF FLORENCE, ITALY.

BUILDING BLOCK.

Application filed May 21, 1924. Serial No. 714,860.

To all whom it may concern:

Be it known that GAETANO PILATI, subject of the King of Italy, residing at Florence, Italy, has invented certain new and useful 5 Improvements in Building Blocks, of which the following is a specification.

The present invention relates to perforated elements for building purposes. These elements are made of any suitable mixtures, for instance of concrete, cement, etc., and are characterized by their being doubly interlocking; that is to say, they are formed in such a manner as to admit of their interlocking both horizontally and vertically.

15 The elements are perforated for the sake of economy and lightness, and in order to impart to the structures in which they are used, resistance to atmospheric influences, such as heat, sound, etc.

20 The perforations or apertures may correspond vertically one to another, or not. In the first case, the insulating air may circulate within the walls. In the second case, on the other hand, there will be a number of 25 insulating zones, having no communication with each other. Besides affording insulation, the apertures or perforations may serve the purpose of containing framing stays or the framing itself.

30 Moreover, the apertures may be multiple, in which case they may either be parallel to each other and in alignment or staggered so as never at any point to present a straight line, or they may also be single, i. e. in a 35 row.

The vertical and transverse interlocking or jointing in the laying of the elements provide spaces for the mortar, so that the mortar used enters a shaped cavity having a 40 large surface of adhesion.

The horizontal jointings, on the contrary, present flat surfaces, over which the mortar may be spread with ease.

45 The elements may be made in various shapes and arrangements. In the accompanying drawings several examples of the commonest arrangements are given, as are also indicated a few examples of construction and jointing.

50 In said drawing Fig. 1 shows in a front view and in cross section, respectively, elements with three staggered rows of apertures; Fig. 2 shows, in horizontal section, two of said elements interlocked. Fig. 3 shows in front view and in cross section, re-

spectively, an element having three apertures parallel to and in line with each other.

Fig. 4 shows, in horizontal section, two of said elements joined together. Fig. 5 is a transverse section showing an element provided at its lower part with three parallel apertures and provided at its upper part with a single gap capable of containing the horizontal beams or the like, of the building. Fig. 6 shows in plan two such elements connected together.

Fig. 7 shows in front view and in cross section respectively, a type of element provided with three staggered apertures, of which the central ones have passages, whereas the side ones are blind.

Fig. 8 shows a plan and horizontal section view of two such elements connected together.

Fig. 9 shows in front view in section and in plan, respectively, an element for the angles of casements, with three staggered apertures.

Fig. 10 represents, respectively, in section, in side view and in plan view, an element especially suitable for the reception of outer shutters or sun-blinds.

Fig. 11 indicates in perspective an example of construction with elements arranged in staggered relation with respect to each other; Fig. 12 is another example in perspective in which are clearly shown the intercommunicating apertures only; and Fig. 13 shows in plan a type of construction with elements having three parallel aligned apertures.

From the drawing it is apparent that the elements —a—, —a— (Figs. 1 and 2, 3 and 4) present vertical, multiple grooves —b—, —b— and longitudinal lateral protuberances —c— which are in communication with the upper skew notches —d—, —d— likewise lateral.

Both the element according to Figs. 1 and 2 and the element according to Figs. 3 and 4 are provided with blind apertures, staggered in the first case, and in the second case, aligned and parallel. The apertures are rendered blind by means of a membrane —x—; this membrane may easily be broken through when the apertures are meant to communicate, or for any other reason.

In Fig. 5 the element —a— is divided into two parts; the lower part being provided

with blind apertures, as usual, whilst the upper part is provided with a gap —e— suitable for the reception of the metallic beam or reinforcement —f— of the building.

5 The projections —c—, and the grooves —d— are similar to those shown in Figs. 1, 2, 3 and 4.

10 Figs. 7 and 8 show an element which also has three staggered apertures with a single transverse groove —g—. This element, too, is provided with projections —c— and grooves —d— which are longitudinal.

15 Fig. 9 is an element suitable for the construction of casement angles, provided with a single transverse groove —g— and with apertures.

20 Fig. 10 is an element of the same type as the foregoing, but adapted to receive in the empty space —h— a sliding shutter.

In the examples of the modes of application according to Figs. 11, 12 and 13, the blocks are seen connected, superposed and cemented together.

25 In Figs. 11 and 13 are further shown examples of vertical reinforcements —i—, located in special vertical gaps —l—.

With this system of elements I obtain a structure which is rigid owing to the fact 30 that, laterally, I have superposed connections, viz: —d— and —e—. Moreover, the upper surfaces of the elements may be spread over with a uniform and smooth

layer of mortar, which on receiving the block immediately above it, containing the 35 blind apertures, penetrates to a certain extent into these blind apertures forming a strong connection especially suited to resist the strain due to lateral thrust.

In order to open the blind apertures, for 40 the purpose of receiving vertical framing or for ventilation, etc., the membrane should be broken through, in any manner, as is shown at —m— in Fig. 11.

Having thus described my invention, what 45 I claim is:

A hollow interlocking building block having between its side faces a plurality of rows of vertical apertures of circular cross-section, flat side faces thereon, ridges and 50 grooves formed on the end faces of the block to interlock with adjacent blocks and to provide pockets for mortar, depending ridges extending from end to end of the lower marginal side edges of the block, grooves extending from end to end of the upper marginal side edges of the block for the reception of the ridges on the block resting thereon, and a flat recess in the under face of the block—between said ridges—for containing the mortar when the blocks are in assembled position.

GAETANO PILATI.

In presence of:

VIRGILIS CAPONI,

CAMILLO BRUNO MANNUCCI.
